ARTIFICIAL BUTTERFLY

Evelyn Shoemaker, Birmingham, Ala.

Application December 5, 1955, Serial No. 550,911

3 Claims. (Cl. 41—10.)

My invention relates to artificial butterflies and the like and to a process for making the same.

In the manufacture of artificial butterflies, birds, and other similar items for decorative purposes, it heretofore has been the custom to fasten the wing covering to the wing outline frames by some form of adhesive or glue. Such prior manner of constructing the wings has been labor consuming and difficult, resulting in high cost of manufacture. Unless such adhesive or glue is waterproof, the fabric or other covering readily comes off if the articles are used to decorate flowers for out-of-doors use such, for instance, as when used to decorate funeral wreaths, and so forth. Further, insofar as I am aware, the portion simulating the body in previous artificial butterflies has been formed by such means as rolling various kinds of material into generally the shape desired and tying it with wire, thread or the like, this also being an expensive operation.

In view of the foregoing it is an object of my invention to provide artificial butterflies and like ornaments in which the diaphanous material forming the wing covering is bonded by heat to the wing outline frames, thus greatly facilitating the manufacture of the wings and securing the covering thereto in waterproof manner.

Another object is to provide articles of the character designated in which the wing outline frames are made of small diameter wire which is covered with a thermo-plastic material, whereby the covering may be attached by laying it over the frame and heating the assembly, thus causing the covering to become imbedded in the thermo-plastic material.

Another and more specific object is to employ a covering of mesh material, preferably of nylon or the like, and to use a wire having a thermo-plastic cover with a melting temperature below the melting or disintegrating temperature of the covering, assuring proper imbedding of the covering in the plastic.

Another object is to provide an article of the character described in which the body is formed of a length of fabric covered wire such as ordinary pipe cleaner-like material bent upon itself at the rear end of the article with the ends thereof diverging at the front, providing a very realistic body portion which is easy to make and easy to assemble on to the wings.

A device illustrating the features of my invention and which also illustrates the method of carrying out my improved process is shown in the accompanying drawings forming a part of this application in which:

Fig. 1 is a plan view of the frame assembled without the pipe cleaner-like body in place;

Fig. 2 is a plan view of the completed article with the pipe cleaner body in place thereon;

Fig. 3 is an end elevational view and showing the wires for attaching the same to flowers or the like;

Fig. 4 is an enlarged detail sectional view taken generally along line IV—IV of Fig. 2 and showing the manner of imbedding the wing covering into the plastic ma-

2

terial surrounding the wire which forms the wing outlines and;

Fig. 5 is a flow diagram showing the steps which I preferably follow in constructing my improved article of manufacture.

Referring now to the drawings for a better understanding of my invention I show in Fig. 1 the frame which forms an artificial butterfly. The outline frame 10 consists essentially of wire which may be bent to the outline shown to form a pair of forward wings 11 and a pair of rear wings 12. The wire used to form all of these may be a single length of wire and the same may be twisted upon itself as shown to form a relatively rigid elongated portion 13 which connects the sets of wings.

As best shown in Fig. 4 the frame 10 may be a copper wire 14, covered with a thermo-plastic insulating material 15. The precise kind of material 15 is unimportant so long as it melts at a temperature less than the melting or decomposition temperature of the material forming the wing covering proper as will later appear.

Placed over the upper and undersides of the wing frames are layers 16 and 17, respectively, of a woven, diaphanous material. In practice this material preferably is of nylon mesh having openings on the order of about $\frac{1}{16}$ inch. While there may be many other materials suited to the purpose at hand I preferably employ nylon because it is waterproof, will not shrink, and may be purchased on the open market in a variety of pleasing shades which are colorfast.

In constructing my improved artificial butterfly or the like I first start by forming the wing frames of the wire 14, connected as shown by the body portion 13. Having formed the device as illustrated in Fig. 1, I next lay over the completed frames a layer of the nylon mesh covering 16. With this material in place I then contact the same with a sadiron which is heated to a temperature above the melting temperature of the thermo-plastic material and below the melting or decomposition temperature of the material forming the covering 16. This has the effect of immediately melting the plastic material 15 of the wire frame and imbedding the mesh material 16 into the surface of the material as indicated in Fig. 4.

Having now secured the layer 16 to the frames I turn the entire device over and repeat the operation by securing thereto the lower layer 17 in the manner just described. With the material secured to the frames I then trim the same with scissors or the like, providing the complete unit, that is, the outline frames covered on both sides with the material forming the covering.

I next bend a length of fabric covered wire such as pipe cleaner material 18 upon itself as shown, spreading the forward ends as at 18a and 18b. I now lay this on the frame, parallel to the central portion 13 thereof and secure the same by wrapping thereabout a wire 19. The wire 19 may be twisted as indicated at 21 on the underside of the article, thereby to leave two elongated ends 21a and 21b. These ends may be used to secure the entire article to a flower arrangement, wreath or the like.

From the foregoing the method of constructing my improved artificial butterfly or the like together with the method of carrying out my improved process will be readily understood. As a specific example of the type of wire which may be employed in fabricating my improved artificial butterflies and the like, I have found that a type of wire called "Plexon pigtail wire" is entirely satisfactory for the purpose at hand. Such wire is a metallic strand covered with a pyroxylin type covering such as nitro-cellulose softened by suitable plasticizer. This particular wire can be bought from the above mentioned company with the plastic material of white or other suitable color. The wire 14 may be copper or otherwise. While the specific nature of the covering 15 around the

wire 10 is unknown to me, suffice it to say that it becomes plastic at a temperature below that at which the nylon mesh is damaged when an iron hot enough to plasticize the wire covering is placed on top of the nylon.

From the foregoing, it will be apparent that I have devised an improved method of fabricating artificial butterflies and the like. Likewise, it will be apparent that my improved article of manufacture is capable of mass production and is extremely attractive and serviceable. In actual practice I have found that my improved articles are extremely weather resistant and that they add an unusual attraction to flower arrangements such as corsages, funeral wreaths and similar flowers.

While I have referred to specifically the manufacture of artificial butterflies and the like, it will be apparent that my invention may be used with equal advantage in the manufacture of other artificial articles such as artificial birds, flowers and similar objects wherein a frame is to be covered with material. Therefore, where the expressions a "butterfly wing" or "wing structure of artificial butterflies" are used, they are intended to embrace such other articles.

While I have shown my invention in but one form, it will be obvious to those skilled in the art that it is not so limited, but is susceptible of various changes and modifications without departing from the spirit thereof and I desire, therefore, that only such limitations shall be placed thereupon as are specifically set forth in the appended claims.

What I claim is:

1. As an article of manufacture an artificial butterfly comprising forward and rear sets of wings, each wing embodying an outline frame of metallic wire covered with a thermo-plastic material having a plasticizing temperature below that of nylon, nylon mesh covering overlying the frames, said nylon mesh material having the strands thereof imbedded in the thermo-plastic material of said frames and extended to the periphery thereof, and a simulated body portion for said butterfly comprising a single length of fabric covered wire bent upon itself and secured to the wings.

5 2. The article defined in claim 1 in which the wing frames are covered on each side with said nylon mesh covering.

10 3. The article defined in claim 1 in which the single length of fabric covered wire is a length of pipe cleaner material.
